H. J. McGREAL.
SOUND REPRODUCING MACHINE.
APPLICATION FILED FEB. 8, 1916.

1,277,096.

Patented Aug. 27, 1918.

UNITED STATES PATENT OFFICE.

HUGH J. McGREAL, OF MILWAUKEE, WISCONSIN, ASSIGNOR OF ONE-HALF TO MICHAEL S. SHERIDAN, OF MILWAUKEE, WISCONSIN.

SOUND-REPRODUCING MACHINE.

1,277,096.

Specification of Letters Patent. Patented Aug. 27, 1918.

Application filed February 8, 1916. Serial No. 76,888.

To all whom it may concern:

Be it known that I, HUGH J. McGREAL, a citizen of the United States, and resident of Milwaukee, in the county of Milwaukee and State of Wisconsin, have invented new and useful Improvements in Sound-Reproducing Machines, of which the following is a description, reference being had to the accompanying drawings, which are a part of this specification.

10 This invention relates to improvements in sound reproducing machines.

It is one of the objects of the present invention to provide a sound reproducing machine having a life size head mounted on the upper portion of the machine and having a horn extending from the reproducer to the head to give the impression that the reproduced sound is coming directly from the head.

20 A further object of the invention is to provide a sound reproducing machine having a divided amplifying horn, one branch of which extends to a head mounted on the upper portion of the machine and the other branch extends downwardly through the machine in the ordinary manner.

25 A further object of the invention is to provide a sound reproducing machine having a divided or branched amplifying horn, and through either or both branches of which the sound may be directed.

30 A further object of the invention is to provide a sound reproducing machine which is of simple construction, is strong and durable and is well adapted for the purpose described.

35 With the above and other objects in view the invention consists of the improved sound reproducing machine and its parts and combinations as set forth in the claims, and all equivalents thereof.

40 In the accompanying drawing in which the same reference characters indicate the same parts in all of the views:

Figure 1 is a vertical sectional view of the improved sound reproducing machine;

Fig. 2 is a horizontal sectional view thereof taken on line 2—2 of Fig. 1;

45 Fig. 3 is a sectional detail view taken on line 3—3 of Fig. 2; and

Fig. 4 is a transverse sectional view taken on line 4—4 of Fig. 1.

50 Referring to the drawing the numeral 8 indicates the casing of a sound reproducing

machine, 9 the cover thereof, 10 the reproducing chamber and 11 the body portion of said machine. The reproducing chamber 10 is provided with the usual turn table 12 upon which the record 13 is placed. The 60 chamber also contains the reproducer 14 of ordinary construction which is hingedly connected to the free outer end of the tubular swing arm 15. The inner end of the swing arm is divided into two tubular branch portions 16 and 17, the branch 16 curving downwardly and the branch 17 curving upwardly and entering an opening 18 formed in the lower horizontal wall 19 of the top cover 9. The downwardly curved branch 16 enters an opening 20 formed in the lower horizontal wall 21 of the reproducing chamber and is revolubly mounted thereon by a swivel connection 22. The upper and lower ends of the branches are in vertical axial alignment to permit the swing arm to freely swing in its arc of movement, and the upper end of the branch loosely enters the opening of the wall of the top cover to permit said top cover to be opened and closed. An 70 amplifying horn 23 is positioned in the body portion of the casing and its smaller end extends to the opening 20 of the wall 21 and is connected thereto and forms a continuation of the downwardly curved branch 75 16. The larger end of the horn terminates at the front wall of the casing and the said front wall directly in front of the end of the horn is covered with a grating or screen 24 to permit the sound to pass therethrough. 80

The top cover 9 is of pyramidal form and the apex is provided with a relatively large opening 25 and has a hollow head 26, resembling a human head, removably mounted on said apex portion. A supplemental amplifying horn 27 positioned in the cover chamber 28 and formed in part of said cover has its smaller inlet end 29 connected to the relatively small wall opening 18 of the cover and forms a continuation of the upwardly 95 curved branch 17 of the swing arm 15. The large discharge end 30 of the supplemental amplifying horn extends to the apex opening of the cover so that all sound waves or vibrations will pass from the supplemental horn and into the head and out of the mouth of the head. If desired the head may be formed of a thin material, such for instance as a silk gauze, or any material which will not interfere with the passage of sound 100 105 110

therethrough. The invention also contemplates the use of heads in resemblance of both sexes so that an appropriate head for the particular record may be used.

- 5 In order to direct the reproduced sound from the swing arm into either one or both branches of the said arm a valve 31 is mounted in the swing arm at the point of junction between the two branches and in a 10 position to close off either branch from the swing arm proper. The valve is formed with a projection 32 which extends into a recessed portion 33 formed between the branches 16 and 17 and is provided with 15 a squared opening 34 to receive the cranked handle 35. The cranked handle 35 extends through and has in part its bearing in a nut 36 which is threaded in the swing arm, and at its inner end portion is provided with a 20 squared portion 37 which fits the squared opening of the valve projection. By screwing the nut 36 so its inner end wall bears against the squared portion of the cranked handle, the frictional engagement between 25 the two parts will hold the valve in adjusted position so that the said valve may be held in a position to close off either branch or it may be held in a central position to permit the sound to pass through both branches.
- 30 From the foregoing description it will be seen that the sound reproducing machine is of very simple construction and is well adapted for the purpose described.

What I claim as my invention is:

- 35 1. A sound reproducing machine, com-

prising a sound reproducing mechanism including a pivoted tone-arm having oppositely extending branches at one end, a pair of fixed amplifying horns separately connecting with each of said branches and having their discharge mouths distinct from each other, and means carried by said tone-arm intermediate the ends of the branches for varying the relative volume of sound passing through the branches and the respective amplifying horns.

2. A sound reproducing machine, comprising a casing, and a removable cover for the same, both said casing and cover being provided with a horizontal wall having a vertical opening therein, said openings being in alignment and the space between said horizontal walls forming a closed reproducing chamber, a sound reproducing mechanism in said chamber and including a tone-arm having an upwardly and a downwardly extending branch, the ends of the branches being free to rotate in said openings, a swivel mechanism for pivotally supporting said tone-arm on the horizontal wall of the 60 casing, a valve carried by said tone-arm at the junction of its two branches for directing the sound through either one, or both branches, and an amplifying horn in the casing below its horizontal wall, and another 65 horn in the cover above its horizontal wall, each of said horns connecting with one of said tubular branches.

In testimony whereof, I affix my signature.
HUGH J. McGREAL.
